Application October 7, 1942, Serial No. 461,124
In Great Britain October 31, 1941

29 Claims. (Cl. 179—16)

This invention relates to telephone and like impulsing systems in which impulses are transmitted as makes and breaks in the impulsing circuit.

When impulses are transmitted over an impulsing circuit, such as a line, they are subject to distortion of the make to break ratio due to the electrical characteristics of the circuit and where a route consists of two or more of such circuits connected in tandem the distortion becomes accentuated and if the impulses are repeated from point to point the distortion becomes cumulative and may reach such dimensions that proper response of the apparatus at the distant end is uncertain.

To this end proposals have been made wherein impulses, when repeated, are repeated in a corrected form, either by recording the received impulses and generating and transmitting new and perfect impulses, or by applying a correction to received impulses which determines a minimum of maximum duration for the make and/or break of the impulses.

The present invention provides impulse modifying arrangements whereby the form of the impulses transmitted or received can be modified to give repeated impulses a desired form, that is, a desired make to break ratio, which permits of the introduction of a correction to compensate for any ratio distortion of the impulses during their transmission from point to point.

In the present invention impulse modifying arrangements are provided permanently associated with the impulsing circuit and comprise apparatus which is adapted to provide a fixed increase or decrease in the length of the make or break component of an impulse as delivered to the arrangements with a corresponding alteration of a break or make so that the impulse as repeated by the arrangements have a desired make-to-break ratio. The modification can be applied at the receiving point by modifying the impulses received thereat to have the desired make-to-break ratio, or alternatively the modification can be made at the transmitting end of the circuit so that the modification is entirely, or to a desired extent, nullified on the impulses reaching the receiving end.

The fixed modification may take the form of a retardation or hastening of the operation and/or release of an impulse responsive relay or relays by a predetermined amount by which a fixed period is subtracted from or added to the time during which a relay is operated consequent on the receipt of an impulse which determines the

length of one of the components of a repeated impulse. This may be accomplished by a single relay which may have its operation or release delayed either to shorten or lengthen a component of the repeated impulse. Alternatively it may be accomplished by a pair of relays one of which is delayed in operation and the other delayed in its release to bring about the said shortening or lengthening of the repeated impulse.

The delay in operation of a relay is conveniently accomplished by means of an impedance in series with the operating coil of the relay, and the delaying effect of the impedance may be controlled by a resistance shunted across it, the resistance preferably being adjustable to enable adjustment to be made.

The delay in release of a relay may conveniently be accomplished by means of a condenser which is charged or discharged for the duration of the component prior to that to be repeated, and when the component to be repeated follows, the condenser is connected to be discharged, or charged, in a circuit which acts to assist the operating coil, it being arranged that the discharge, or charging, current persists after the termination of the impulse component to maintain the relay operated for a period equivalent to the modification to be made. A resistance is preferably connected in the charging, or discharging, circuit to determine the rate of charge, or discharge. A similar arrangement can be used to delay the operation of the relay, the charge or discharge circuit of the condenser being connected up on the commencement of a component to be repeated, so as to act in opposition to the operating coil of the relay.

The fixed modification as applied is adjusted at one speed of impulsing but being fixed is independent of any variation in the speed of impulsing. The modification may be predetermined and set so that the desired ratio of make-to-break is repeated. This predetermined may be carried out by transmitting impulses of a desired make-to-break ratio over the impulsing circuit and adjusting the modifying arrangements at the incoming end of the circuit until the repeated impulses have the desired ratio. Alternatively the modifying arrangements may be associated with the outgoing end of the circuit and impulses of a modified ratio transmitted, the modified ratio being varied until the impulses received at the incoming end of the circuit have the desired ratio.

In order to compensate for a variation in speed

of impulsing it may be desirable to increase or decrease the effect of the fixed modification by an amount depending on the variation in this speed and to provide for this a further or auxiliary modification dependent on the duration of the components of the impulses may be applied, the fixed and auxiliary modifications being added algebraically in the impulse modifying apparatus. This auxiliary modification may be applied by means of an auxiliary relay the operating or releasing times of which are hastened or delayed to add algebraically the requisite amount to the fixed modification. Such a relay is given a delay period under normal conditions of repetition, that is, where no auxiliary modification is required, so that to make an auxiliary modification its operation may be hastened or further delayed. Under such normal conditions its releasing lag should equal its operating lag. The delay in operation may be accomplished by means of an impedance in series with the operating coil of the relay, and in its release by means of a condenser arrangement, as previously referred to in connection with the fixed modification.

As the auxiliary modification required is dependent on speed, it is convenient to determine the auxiliary modification by measuring one of the components of an impulse, preferably the break, as actually received and with the fixed modification algebraically added to it and compare this with a corresponding correct component at the speed at which the fixed modification was made, the auxiliary modification to be made depending on the excess of the former over the latter.

This may be accomplished by the use of a constant period relay which is given a delay in operation equal to the break component of an impulse at the speed at which the fixed modification was made, that is, as will be repeated at this speed after the fixed modification has been made, the relay operating at the end of this period and remaining operated during the said excess period to determine the auxiliary modification to be brought about. The delay in operation of the constant period relay may be imposed by a series impedance which may be regulated by a resistance shunting it.

In the case where it is desired by the auxiliary modification to bring about a shortening of the repeated make component and a lengthening of the break component by a requisite amount, the operating lag of the auxiliary relay may be increased. This is conveniently accomplished by the use of a condenser which is charged during a make period through a coil of the auxiliary relay acting in opposition to the operating coil thereof, the condenser during the preceding break period being discharged an amount depending on the aforesaid excess of the break period, e. g. by the use of the constant period relay. During the subsequent make-period as the charging circuit for the condenser includes a differential coil of the auxiliary relay, the operation of the relay will be delayed an amount depending on the time it takes for the opposition to be overcome by the current passing through the operating coil of the relay.

In the case where it is desired by the auxiliary modification to bring about a shortening of the break component and a lengthening of the make component, the operating lag of the auxiliary relay may be decreased, and a convenient way to accomplish this is to delay the operation by

an amount depending on the aforementioned excess period. The decrease in the operating lag may be accomplished by producing a flux in an impedance connected in series with the operating coil of the relay to an amount depending on the said excess period so that the impedance is less when the operating circuit is closed, producing a consequential quicker operation of the relay.

A further manner in which to bring about the auxiliary modification is to provide the auxiliary relay with a coil in addition to its operating coil which additional coil is arranged to act either to assist or to delay the operation of the auxiliary relay for a period equivalent to the auxiliary modification required, e. g. as determined by the said excess period. In this case a condenser may be charged by a suitable amount during said excess period and during the subsequent make period be caused to discharge in one or other direction through the additional coil either to oppose or to assist the operation of the relay by an amount dependent on the value of the charge, that is, on the excess period.

In a further manner of applying the auxiliary modification in the aforementioned arrangement employing a pair of relays to effect the main correction, condensers may be employed which are adapted to be charged (or discharged) during the break and make periods of a received impulse respectively, and connected in a discharge (or charging) circuit, either to delay the operation of the said one relay or the release of the said other relay.

In order to enable the adjustment of the arrangements there may be provided at the end of the circuit from which the impulses are transmitted an impulse sending arrangement which is adapted to deliver impulses at a predetermined rate and ratio; and at the receiving end means to measure the speed and ratio of the impulses repeated thereat. In order that a test of the adjustments may be carried out locally at the receiving end, there may be provided thereat arrangements which are adapted to transmit impulses similar to the impulses as received at the receiving end of the circuit. Thus conditions simulating working conditions can be applied at the receiving end, and the results of the correction made measured.

In the accompanying drawing, in Figs. 1 to 3, are illustrated by way of example several ways in which the above and other features not previously mentioned may be carried into effect, the arrangements of the several figures being described in the following description. The arrangements are described and illustrated as associated with an impulsing circuit comprising a line between two telephone exchanges, the arrangements being used to apply a modification or correction to the impulses as received and distorted by the impulse distorting characteristics of the impulsing circuit whereby the impulses repeated at the receiving end have substantially the same ratio as the impulses originally transmitted from the transmitting end. As in the following arrangements the modification of the impulses is in the nature of a correction, the latter term will be used throughout the description.

In Fig. 1 of the drawing the apparatus shown in the rectangle enclosed by the dot-dash line at the top left-hand corner represents a portion of the apparatus at the outgoing exchange OE from which the impulses are transmitted to the incoming exchange IE over the junction line

JCT. The apparatus in the transmission circuit at the exchange OE is as employed in known practice and therefore only that part of the apparatus necessary to enable a complete understanding of the invention is shown and a general description thereof given. This apparatus is shown as an impulse repeater circuit comprising a repeater coil transmission bridge to the incoming side of which is connected an impulse relay AO over contacts *do1* and *do2* of a bridge relay DO connected to the outgoing side of the bridge and to the junction JCT over contacts *ao* of the impulse relay and contacts *ha01* and *ha02* of a switching relay which is operated when a preceding selector switch tests into the free impulse repeater circuit. Contacts *co* of a relay which is operated at the first impulse break and thereafter remains operated throughout the remainder of the impulse train, are adapted to short-circuit the outgoing side of the bridge to give a clean impulsive loop during impulse repetition by the contacts *ao*. These latter contacts *ao* in their normal position also short-circuit the outgoing side of the bridge, the object being to provide a circuit which absorbs inductive surges from the repeater coil on the relapse of contacts *ao* during the first impulse repetition to prevent the induction of currents in the incoming side of the bridge which may interfere with the performance of relay AO. These contacts *ao* have a resistance and a capacity in series shunted across them to prevent sparking thereacross. The outgoing side of the bridge is connected via intermediate distribution points (not shown) in the exchange to a main distribution frame where it is connected over a heat-coil and arrester unit MFO to the junction line JCT. This unit MFO is of the usual kind and, in effect, comprises break-jack points into which a test plug or shoe TS may be plugged to isolate the connections internal and external to the exchange and connect them to some testing apparatus.

The operation of the apparatus thus far described is, in general, as follows. When the repeater circuit is seized by a preceding selector switch, relay AO and the switching relay controlling contacts *ha0* operate, the former relay over the preceding loop and the latter consequent on the operation of a slow relay by the operation of relay AO. The outgoing side of the repeating coil is thus looped across the junction JCT in series with rectifier MRA to the distant exchange where it meets battery connections, the direction of connection of the rectifier MRA in series with the relay DO being such as to prevent current flow through relay DO with the battery conditions now prevailing. Relay AO responds to the incoming impulse train and by its contact *ao* repeats these impulses to the junction JCT and the distant exchange. On the first break a slow-releasing relay controlling contacts *co* operates, and remains operated for the remainder of the impulse train, the contacts *co* short-circuiting the outgoing side of the repeater coil and thereby providing a clean impulsive loop to the distant exchange. On the cessation of the impulse train the contacts *co* relapse, and after the connection has been completely set up and the called party answers, the battery conditions on the junctions are reversed and relay DO operates in series with rectifier MRA, the rectifier MRA no longer being effective, and at its contacts *do1* and *do2* reverses the bat-

tery connection to the incoming loop to effect a supervisory operation such as metering.

It is desirable for testing purposes, as will be referred to later, to provide arrangements whereby impulses of a desired speed and ratio can be transmitted from the exchange OE to the exchange IE. This may be done by means of a mechanical device such as an impulse sender, or it may be done by purely electrical arrangements as represented in the broken line enclosed rectangle TEO. These arrangements terminate, over a flexible cord, in a plug or test shoe TS, so that they may be connected to the junction line JCT by plugging into the main frame unit MFO. The testing equipment shown comprises an impulsive relay *XA* and an interrupting relay *XI*. Contacts *xa1* of relay *XA* are adapted to apply a loop to the junction line on the operation of the relay, and shunting these contacts are a condenser *QE* and resistance *RS* in series, provided to simulate the capacity and resistance shunt across contacts *ao*, that is, to prevent sparking that may occur at contacts *xa1* on opening, and also to dissipate any surges that may occur in the line on the opening of the contacts. Contacts *xa2* control a ratio measuring meter *XM* for indicating the ratio of make to break of the generated impulses, the meter having an adjustable resistance *R9* in series with it.

The relay *XI* has two windings connected in parallel with each other, one winding (the right hand) having a condenser *QD* connected in series with it. The ratio of make to break and speed of the impulses delivered by the equipment depends upon the times of operation and release of relay *XI* which are determined by the capacity of condenser *QD*. The apparatus is started in operation by throwing key *XSK* which at contacts *XSK2* closes an obvious circuit for relay *XA* over contacts *xi2* and relay *XA* operates. Contacts *xa1* close the loop circuit, and contacts *xa2* the circuit for the ratio meter *XM* as before described.

Contacts *XSK1* close the circuit for relay *XI* over self-interrupter contacts *xi1* of the relay. The operation of relay *XI* is delayed in operation by the condenser *QD* for two reasons, that is, it delays the building up of the current in the left hand operating winding of the relay, and further, the direction of the charging current for the condenser through the right-hand winding of the relay is such as to oppose the effect of current flow in the left-hand winding. When the charge in the condenser has built up to a particular value, relay *XI* operates, and in doing so interrupts its own operating circuit at contacts *xi1* whereupon condenser *QD* discharges through both windings of relay *XI* in series in such a direction that the windings aid each other, the relay being maintained operated in this manner for a predetermined period after its operating circuit is opened. On the relapse of the relay its circuit is again closed and the operations repeated so long as key *XSK* is operated. Relay *XA* is made to follow the relay *XI* by means of contacts *xi2* and thus to apply makes and breaks to the loop circuit in a predetermined ratio. An adjustment for speed can be obtained by varying the capacity of condenser *QD*. At the exchange IE the junction is connected through an arrester unit MFI, and further intermediate distribution points (not shown) at that exchange to the apparatus which is shown as an impulse repeater comprising a repeating coil transmission bridge

substantially identical with that provided at exchange OE with the exception that the impulse relay AI does not directly repeat the impulses to the outgoing side of the bridge, but only does so indirectly through impulse correcting apparatus. The outgoing side of the bridge may for example extend to a selector at a local exchange or directly to a further junction line or over a junction selector.

The correcting apparatus includes a relay AA which controls an auxiliary relay AB, contacts *ab2* of the latter being included in the outgoing circuit from the repeater circuit. The relay AA is included in a circuit which is adjustable to correct for the main impulse distortion characteristics of the junction, whilst the auxiliary relay AB is included in an auxiliary correcting circuit which corrects for the distortion introduced by a variation from a predetermined speed of the speed of impulsion. These arrangements will be described in detail together with the impulse generating and testing equipment TEI after the general operations have been described.

When the junction line JCT is taken into use at the preceding exchange OE, the loop applied from the latter completes the circuit for relay AI over the arrester and heat coil unit MFI, break jack BJ, the purpose of which will be described hereinafter, coils of the repeater coil, contacts *d11* and *d12*, and relay AI operates. At contacts *ai1* an obvious circuit is closed for relay BIR and for BI over the test jack TJ5, the springs of which under normal conditions are bridged by a link L, and relay BI operates. A circuit is now closed over contacts *bir1* and *ai1*, coil (I) of the impedance coil RA1, and relay AA, and this relay operates. On the operation of relay AA a circuit is closed over contacts *bir3 aa 2*, coil (I) of impedance coil RA2 and left-hand coil of relay AB and relay AB operates. A loop to the circuit ahead is thereupon closed over contacts *bi4*, coils of repeating coil in series with rectifier MRC, contacts *ab2*, *bi2* and *bi3* and the circuit ahead is taken into use. Relay DI does not operate as the rectifier MRD is non-conducting to current in the direction obtaining, and rectifier MRC shunts the relay.

Relay AI responds to the impulses transmitted from exchange OE and repeats them to relay AA at contacts *ai1*. Relay AA in turn repeats the impulses to relay AB which at contacts *ab2* repeats the impulses to the circuit ahead. On the relapse of relay AI to the break portion of the first impulse relay CI is operated in a circuit over contacts *ai2* and *bi4*. Relay BI is the usual release relay and remains operated throughout the break portions of the impulse train and relay CI, due to its being slow to release remains operated throughout the make portions, being energised at each break, and releases at the end of the train. At contacts *ci2* an obvious circuit is closed for the supervisory lamp SY the purpose of which will be referred to later. At contacts *ci1* the outgoing side of the transmission bridge is short-circuited to provide a clean impulsion loop ahead.

When the distant party answers, the direction of current over the positive and negative conductors is reversed and relay DI operates. At contacts *d11* and *d12*, the battery connections to the preceding circuit over relay AI are reversed, resulting in the operation of relay DO at exchange OE as previously described.

The distortion of impulses during transmission over an impulsion circuit at any one particular

speed of impulse transmission may consist of a lengthening or a shortening of the make period of an impulse and a corresponding shortening or lengthening, respectively, of the break period according to the characteristics of the circuit. This distortion is referred to hereinbefore and after as the main or fixed distortion. To correct for this distortion a main or fixed correction is applied.

Distortion is also likely to occur due to variation of the speed of impulsion, such a variation of speed occurring owing to the difficulty of ensuring that the several impulse transmitting apparatus from which impulses are likely to be received all transmit impulses at a nominal speed of impulsion. For example, in the case of a decrease of speed both make and break periods of an impulse are lengthened beyond that obtaining at a nominal speed and with an increase of speed the components are shortened. To correct for this distortion a ratio or auxiliary correction dependent on the speed of impulsion or lengths of the components is called for.

Thus distortion through variation in speed of impulsion may be similar or opposite to the main or fixed distortion produced at one particular speed of impulsion.

It will be appreciated therefore that a fixed correction for compensating for the main or fixed distortion of the impulsion circuit when considered alone can be made at any speed of impulsion, preferably the average speed of impulsion, but when a variation in speed of impulsion is to be catered for it is desirable for the main or fixed correction to be made at one end of the range of anticipated impulsion speeds and an auxiliary correction for variation of speed applied when the speed departs from this particular speed.

For this purpose in the particular arrangements described and illustrated it is arranged that the auxiliary correction has its maximum effect at a speed of impulsion different from that at which the main or fixed correction is made, and its minimum effect at the latter speed. It is therefore convenient to make the main or fixed and auxiliary corrections at the opposite ends of the speed range likely to be met with. It is immaterial at which limits of this speed range the two corrections are carried out, but it is desirable that the auxiliary correction applied should be in the same sense as the variation of the length of impulses. This condition is obtained if the main or fixed correction is made at a higher speed than the auxiliary correction. For example, when the fixed correction is made at a speed higher than the auxiliary correction, as the speed of impulsion increases from the lower to the higher speed, resulting in a shortened impulse, the auxiliary correction will become less i. e. in the same sense. If, on the other hand the main or fixed correction is carried out at a speed lower than that at which the auxiliary correction is made, the auxiliary correction will diminish as the speed decreases from the higher to the lower limit, that is, as the impulses lengthen, and therefore be in an opposite sense.

In the arrangements to be described hereinafter it is assumed that the main or fixed correction is carried out at a higher speed of impulsion, e. g. 12 i. p. s. than the auxiliary correction e. g. 7 i. p. s.

In Fig. 1 of the drawing the main correction is carried out by means of an impedance coil RA1, variable resistance R1 shunting coil (I) of

this impedance coil, variable resistance R2 shunting relay AA, condenser QA and resistance R6. The effect of coil (I) of impedance RA is to delay the rise of current in relay AA, the effect becoming less as the resistance R1 is decreased. Resistance R2 and condenser QA delay the release of AA by an amount dependent on the value of resistance R2 and the charge existing in condenser QA. The condenser QA is fully charged over resistance R6 and contacts *aa1* in their normal position (as shown) during each break period, that is, at each relapse of contacts *aa1*, resistance R6 preventing sparking at contacts *aa1* on their relapse.

To compensate for a gain in the make period of an impulse the value of resistance R1 is increased so that its shunting effect on coil (I) of retard coil RA1 is less whereby the retard coil has a greater effect in delaying the rise in current in the circuit for relay AA and the relay is caused to operate more slowly and delays the commencement of the repeated make period by a required amount. Resistance R2 is set at a maximum so that the delay in release is negligible.

Where there is a loss in the make period of an impulse, the adjustment required is to decrease the resistance of R1 and also that of R2 so as to increase the effect of the discharge current QA through AA when relay AI releases at the end of the make period, resulting in a shorter operating period and an increased releasing lag of relay AA whereby a lengthening of the repeated make period takes place.

The coil (II) of the retard coil RA1 is wound differentially to coil (I). Thus at each release of relay AI, coil (II) of RA1 is connected up over contact *aa1* to produce a magnetic flux opposite to coil (I), whereby any remanent flux is counteracted. In this manner it is ensured that the magnetic condition of retard coil RA1 is the same at the commencement of each make period which in turn ensures that the operating lag of relay AA is maintained constant for every impulse and is independent of the speed of impulsing.

The value of the resistance R6 is such as to ensure that condenser QA is always brought to the same constant condition of charge at each break period. This will ensure that the release lag of relay AA is maintained constant.

The auxiliary correction, which is carried out at a slower speed of impulsing than that at which the main correction is adjusted, is accomplished by the circuit arrangement comprising relay AB and constant period relay AY, and other apparatus illustrated. The arrangement provides for correcting a change in the gain or the loss in the length of the make period brought about mainly by a decrease or increase in the speed of transmission of the impulses. The circuit arrangement is connected up to correct for a gain of make with the key K in its normal position, as shown, whereas the key is operated to correct for a loss of make. As both corrections include varying the operating lag of relay AB, that is, either shortening or lengthening it, it is necessary that the relay should have considerable operating lag and so that its effect is zero when correction is not necessary, the releasing lag should be equal to the operating lag. The operating lag is obtained by connecting the operating coil (left-hand coil) of relay AB in series with coil (I) of retard RA2 shunted by a fixed resistance R3. The release lag is controlled by

condenser QC charged over a resistance R7 to the same state of charge at each release of relay AB, that is, during each break period. This ensures that condenser QC is in the same state of charge at the beginning of each break period and thereby has a constant effect on the release lag of relay AB.

To correct for a distortion brought about by a variation in the ratio due to change in speed of impulsing, relay AY is arranged by means of a retard coil RB and shunting resistance R4, to have an operating lag equal to the break period at the speed at which the main correcting element is adjusted.

With a change of ratio due to a decreased speed of transmission of the impulses, both the make and break periods become longer. To compensate for this condition the key K occupies the position shown, that is, unoperated.

During the make period preceding the break, condenser QB is charged to a constant value over a circuit including contacts *aa3*, key contacts K1, and the right-hand coil of relay AB. When relay AA releases at the beginning of the break period, the circuit of relay AY is closed over contacts

bir3 and *aa2*, and relay AB releases after its slow to release period imposed by condenser QC to repeat the break to the circuit ahead at contacts *ab2*. Relay AY operates at the termination of a break period at the speed at which the main corrector was adjusted and a discharge circuit for condenser QB is closed over contacts *aa3*, key contacts K2, variable resistance R5, and contacts *ay1* and *bir2*, the rate of discharge of the condenser being determined by the adjusted value of resistance R5.

On the operation of relay AA at the commencement of the next make period, the discharge circuit is opened and condenser QB is again connected in circuit with the right-hand coil of relay AB. The condenser QB, discharged an amount dependent on the excess of the break period received over that at the speed at which the main corrector was adjusted, commences to charge up again and the direction of the current flow in the right-hand coil of relay AB is such as to oppose the main operating current and delays the operation of relay AB until the opposition becomes ineffective. This delay in operation of relay AB is therefore dependent

on the length of the said excess.

The value to which the resistance R5 is adjusted depends upon the amount of the distortion to be corrected.

To counteract a loss of make, the key K is thrown to its operated position. In this case it is required that the operation of relay AB shall be hastened, and in order to do this the impedance of retard coil RA2 is reduced by an amount of premagnetisation dependent on the said excess of the preceding break period. To accomplish this the growth of flux in coil RA2 must be slow in order that the required amount of premagnetisation corresponds to the excess break.

This is done by the use of the retard RA3, the two coils of which are connected to act in opposition to each other. During the make period and during the period corresponding to a break period at the speed at which the main corrector was adjusted, coil (II) of retard RA3 is energised over contact *bir2* and *ay1* to produce a magnetic flux in a particular direction. When relay AY operates at the end of the said break period, and whilst it remains operated throughout the excess break period, a circuit is closed over resistance R5 adjusted to a position depending on the

correction to be made, key contact K2 (operated), coil (I) of retard RA3 and coil (II) of retard RA2. In this circuit the direction of current in coil (I) of retard RA3 is such as to produce a flux in opposition to that already built up by coil (II) and this delays the rise of current in coil (I) and in consequence in coil (II) of retard RA2, the rate of rise also depending on the resistance R5. Therefore the value of the flux existing in retard RA2 when relay AA again operates to the next make period is approximately proportional to the excess break period, and the time of operation of relay AB is lessened by an amount corresponding to this excess. Thus in effect a portion has been subtracted from the break period and added to the make period as repeated.

The apparatus enclosed in the broken line rectangle TEI is an impulse generating and receiving equipment, generated impulses being delivered to a plug associated with a break jack BJ in the repeater circuit, whilst impulses are accepted over a plug adapted to be plugged into test jack TJ2. This apparatus may be adjusted to simulate impulses as received over the junction JCT.

The operations involved in the generation of impulses of a determined frequency and ratio are as follows. Key YSK is operated and a circuit is thereupon closed over contacts YSK1 and y1 for relay YI which operates after a predetermined interval as determined by the capacity of condenser QF (as described in connection with relay XI, at exchange OE). Also a circuit is closed over contacts YSK2 and y2, upper coil of relay XRT, and impedance XRA shunted by a resistance R11. Relay XRT operates after a lag as determined by the effects of impedance XRA and resistance R11. On the operation of relay XRT an obvious circuit is closed for relay YA and relay YA operates. At contacts y1 a loop circuit is closed over the cord terminating in the plug which is adapted to be plugged into break jack BJ. At contacts y2 a loop is closed to the points of a test jack TJ3 which is to enable the ratio measuring meter to be directly connected to the contacts to indicate the ratio of the impulses actually being transmitted.

When relay YI operates it disconnects its own circuit at contacts y1, and the circuit for relay XRT at contact y2.

The condenser QF and resistance R10 in series across contacts y1 are provided to absorb any surges that may occur across the contacts, and simulate the conditions of the impulse repeating contact at the outgoing end of the line JCT.

The routine to be followed for setting the main and auxiliary correcting apparatus is as follows. The test plug TS at exchange OE is plugged into the arrester unit MFO, thus connecting the testing equipment TEO to the junction JCT. At exchange IE the plug associated with the jack TJ2 is inserted into the jack. Also the link L is withdrawn from test jack TJ5 and inserted in test jack TJ4, thus disconnecting the circuit of relay BI and preparing the circuit of relay CI independently of contacts b1 so that relay CI will operate on the release of relay AI and remain operated during the reception of impulses. As relay BI cannot be operated any impulses received cannot be passed forward to the circuit or junction ahead.

The testing equipment TEO at exchange OE is set to deliver impulses at a speed greater than the average to be transmitted over the junction JCT but in the same ratio. For example, if the aver-

age speed of impulsion is 10 impulses per sec., then TEO may be set to deliver 12 impulses per sec., the break-to-make ratio at both speeds being the same.

5 The impulses are received by relay AI and repeated to relays AA and AB and thence over contacts ab2 and test jack TJ2 to the ratio meter YM which has a regulating resistance R12 in series with it. The main correction is accomplished by adjusting resistances R1 and R2 until the correct make to break ratio of the impulses is repeated at contacts ab2 as indicated by the meter YM.

10 When the requisite main correction has been made, the auxiliary correction is performed at a lower speed, for example, 7 impulses per sec. and the necessary regulation made for loss or increase of make by adjusting resistance R5 as will now be understood.

15 When the adjustments have been made the testing apparatus is disconnected from the junction in preparation for normal operation. When relay AI is released the circuit of relay CI is closed at contacts ai2 until the link L is withdrawn from the jack TJ4, with the result that the circuit for lamp SY is maintained to indicate that normal conditions have not been established.

20 If at any time it is desired locally to test the 30 correcting arrangements for correct operation, the associated plug is inserted into the test jack BJ, as are also the plugs associated with jacks TJ1 and TJ2, and the link L is changed over to the test jack TJ4 as before. The junction JCT is isolated from the bridge at the break jack BJ and 35 busy tone over wires BT is applied to the junction over the jack TJ1 to indicate to a calling party at exchange OE that the junction is not available. The test can now be carried out by setting the testing equipment TEI to apply impulses to the 40 correcting equipment simulating those which would be applied over the junction JCT as determined on previous tests. If any variations are indicated, a full test can again be carried out from the exchange OE.

45 In Fig. 2 is illustrated a modification of the auxiliary correcting arrangement of Fig. 1 the main difference being that the condenser QB, instead of being partially discharged to measure the excess break period and control the delay or 50 more rapid operation of relay AB, receives a charge dependent on this excess break period and controls the relay AB accordingly.

The impedance RA2 in series with the left-hand operating coil of relay AB has only one coil. 55 The inherent operating and releasing lags of relay AB are determined in a manner identical with that described in connection with Fig. 1.

60 The key K occupies its normal position (as shown) to correct again in the make period on a decrease in speed of impulse transmission, and is operated to correct a loss in the make period at a low speed of impulse transmission.

65 The manner in which an auxiliary correction is applied for a gain in the length of the make period is as follows: When relay AY operates, a charging circuit for condenser QB is closed over contacts aa3, ay1 and the series resistance R5. At the termination of the break period when relay AA re-operates, a discharge circuit for condenser QB is closed over key contacts K2, upward through the right-hand coil of relay AB, key contacts Ki, and contacts aa3. The direction of this discharge current is such as to oppose the operating current in relay AB resulting in a delay in 70 operation of the relay by an amount depending

on the charge existing in the condenser, that is, on the extent of the excess break period over the break period at the speed at which the main correction was adjusted.

In the case of a shortened make period, the key K is thrown to its operated position. As before, during the excess break period condenser QB receives a charge to an amount dependent on the excess of the break period. At the termination of the break period when relay AA re-operates, a discharge circuit for condenser QB is closed over key contacts K2, downward through the right-hand coil of relay AB, impedance RA4, key contacts K1 and contacts aa3. The current in this circuit is such as to assist the operating current in the left-hand operating coil of relay AB resulting in a quicker operation of the relay by an amount depending on the excess of the break period. The purpose of impedance R4 is to prevent a too rapid discharge of the condenser QB.

In Fig. 3 is illustrated a modification of the arrangements for carrying out the main and auxiliary corrections. As far as possible similar references are used to indicate parts carrying out functions similar to those carried out by like parts in Fig. 1. In general the main and auxiliary corrections are carried out by the adjustment of the operating lag of relay AA and releasing lag of relay AB. For obtaining the appropriate auxiliary corrections two keys AK and BK are provided, the key AK being provided for effecting an auxiliary correction to compensate for an increased make period and key BK for a decrease in the make period at a low speed of impulsing.

As in Fig. 1 relay AA is caused to follow the impulse relay (AI) and relay AB to follow relay AA to repeat the impulses to the circuit ahead.

A main correction above is carried out with the keys AK and BK occupying their normal positions as shown.

In order to effect a compensation in the make to break ratio of an impulse as received where the main distortion is such as to produce a lengthened make period, the resistance R1 shunting the impedance coil RA1 in circuit with the left-hand operating coil of relay AA is adjusted to delay the operation of relay AA by the amount of the excess of the make period received over the make period to be repeated.

Conversely, to effect compensation of the ratio where the main distortion produces a shortened make period the actions are as follows:

There is provided a condenser QC which during the time relay AB is not operated, that is during a break period, is charged in a circuit including resistance R1, the condenser being fully charged during each break period. On the operation of relay AB at the end of the break period a discharge circuit for condenser QC is closed over the right-hand winding of coil AB, and the condenser discharges through this coil in such a direction as to assist the operating current. The resistance R3 is adjusted to determine the rate of discharge of the condenser QC so that the discharge continues after the termination of the make period of impulses as received to maintain relay AB operated for a period equal to the amount to be added to the repeated make period.

Thus by adjustment of resistance R3 relay AB can be made to release more slowly than its normal release period by an amount corresponding to the distortion of the break period.

which amount is added to the repeated make periods.

The auxiliary correction to compensate for a lengthened make, is obtained by the operation of key AK alone. When this key is operated and during the break period of an impulse, condenser QA is charged over a circuit including contacts of key AK, contact aa2 of the impulse relay, and resistance R6 and condenser QA receives a charge depending on the length of the break period and the value to which resistance R6 is adjusted. When the impulse relay (AI) operates at the end of the break period, a discharge circuit for condenser QA is closed over the right-hand coil of relay AA. The direction of this discharge current is opposite to the main operating current and the opposition results in a delay in the operation of the relay until such time as the effects of the main current overcome those of the discharge current, this period being arranged by the adjustment of resistance R6 to a value for determining the requisite rate of discharge to correspond to the excess make period.

In order to compensate for a decreased make period at a low speed of impulsing, key BK is alone operated. In this case during a make period when the impulse relay (AI) is operated, condenser QB receives a charge depending on the length of the make period and the value of the adjustable resistance R5. At the termination of the make period when the impulse relay releases, a discharge circuit for condenser QB is closed over the left-hand coil of relay AB. The duration of this current is such as to produce a similar magnetisation of the relay as the operating current with the result that relay AB is delayed in release for a period until the discharge current falls below a value which will maintain the relay operated, this period, by the adjustment of the rate of charge, as determined by the setting of resistance R5, corresponding to the excess break. The effect, therefore, is to subtract a portion from the received break and add it to the repeated make.

It will be appreciated that the exemplary arrangements described above can be modified in that the correcting arrangements may be situated at the outgoing end of the junction, that is, at exchange OE. In this case, the correction in effect, is a negative one which is nullified by the impulse distorting characteristics of the junction so that the impulses received at exchange IE will have the same make to break ratio as the original impulses at exchange OE and may directly be repeated in an undistorted form at exchange IE. The correcting arrangements as described above are suitable for this purpose.

What I claim as new and desire to secure by Letters Patent is:

1. In an impulsing system, an impulsing circuit, means for alternately opening and closing said circuit thereby to generate impulses, each impulse having a make component and a break component, an impulse repeater permanently associated with said circuit for receiving and repeating said impulses, said repeater including means for causing the make component of each repeated impulse to be a fixed amount shorter than the make component of the corresponding received impulse and for causing the break component of each repeated impulse to be a fixed amount longer than the break component of the corresponding received impulse, whereby the

make-to-break ratio of the repeated impulses is different than that of the received impulses.

2. In an impulsing system, an impulsing circuit, means for alternately opening and closing said circuit thereby to generate impulses, each impulse having a make component and a break component, an impulse repeater permanently associated with said circuit for receiving and repeating said impulses, said repeater including means for causing the make component of each repeated impulse to be a fixed amount longer than the make component of the corresponding received impulse and for causing the break component of each repeated impulse to be a fixed amount shorter than the break component of the corresponding received impulse, whereby the make-to-break ratio of the repeated impulses is different than that of the received impulses.

3. In an impulsing system, a line having an impulse responsive device connected thereto, an impulsing circuit, means for alternately opening and closing said circuit thereby to generate impulses, each impulse thus having a make component and a break component, an impulse repeater associated with said circuit for receiving said impulses and repeating them over said line to said device, said repeater including means for causing one of said components of each repeated impulse to be a fixed amount longer than the same component of the corresponding received impulse and for causing the other component of each repeated impulse to be a fixed amount shorter than the same component of the corresponding received impulse, said line having electrical characteristics such as to nullify said repeater's modification of the impulses, whereby the impulses received by said device have the same make-to-break ratio as the impulses generated in said circuit.

4. In an impulsing system wherein impulses are generated at different speeds at different times and said impulses consist of breaks and makes of an impulsing circuit, an impulse repeater associated with said circuit for receiving and repeating said impulses, said repeater including means functioning independently of the speed of the received impulses for causing the make component of each repeated impulse to be a fixed amount longer than the make component of the corresponding received impulse and for causing the break component of each repeated impulse to be a fixed amount shorter than the break component of the corresponding received impulse, whereby the make-to-break ratio of the repeated impulses is different than that of the received impulses, a second impulse repeater connected to the output of said first repeater for receiving and repeating the impulses repeated by said first repeater, said second repeater including means for making an additional change in the make-to-break ratio of the repeated impulses in accordance with the speed at which impulses are received by said second repeater.

5. In an impulsing system wherein impulses are generated at different speeds at different times and said impulses consist of breaks and makes of an impulsing circuit, an impulse repeater associated with said circuit for receiving and repeating said impulses, said repeater including means functioning independently of the speed of the received impulses for causing the make component of each repeated impulse to be a fixed amount shorter than the make component of the corresponding received impulse and for causing the break component of each repeated impulse to be a

fixed amount longer than the break component of the corresponding received impulse, whereby the make-to-break ratio of the repeated impulses is different than that of the received impulses, a second impulse repeater connected to the output of said first repeater for receiving and repeating the impulses repeated by said first repeater, said second repeater including means for making an additional change in the make-to-break ratio of the repeated impulses in accordance with the speed at which impulses are received by said second repeater.

6. In an impulsing system, a circuit over which trains of impulses are transmitted, each said impulse being divided into two complementary periods having a certain ratio to each other, an impulse repeater effective to receive and repeat each said impulse, said repeater including means for increasing one period of each impulse by a fixed amount and for decreasing the other period of each impulse by a corresponding amount, whereby each repeated impulse is divided into two complementary periods having a ratio to each other different than said certain ratio.

7. An impulsing system as claimed in claim 6, wherein said means includes a relay and means for varying the operating time and release time of said relay.

8. In an impulsing system, a circuit over which trains of impulses are transmitted, each said impulse being divided into two complementary periods having a certain ratio to each other and the successive ones of said impulses occurring at different speeds in different trains, an impulse repeater effective to receive and repeat each said impulse, said repeater including means functioning independently of the speed of successive impulses for increasing one period of each impulse by a fixed amount and for decreasing the other period of each impulse by a corresponding amount, whereby each repeated impulse is divided into two complementary periods having a ratio to each other different than said certain ratio, a second impulse repeater connected to the output of said first repeater for receiving and repeating the impulses repeated by said first repeater, said second repeater including means controlled in accordance with the speed of successive impulses for making an additional change in the ratio of said periods.

9. An impulsing system as claimed in claim 8, wherein said last means includes a relay and means for varying the operating times and release times of said relay.

10. In an impulsing system, a circuit over which trains of impulses are transmitted, each said impulse being divided into two complementary periods having a certain ratio to each other and the successive ones of said impulses occurring at different speeds in different trains, an impulse repeater effective to receive and repeat each said impulse, said repeater including means functioning independently of the speed of successive impulses for increasing one period of each impulse by a fixed amount and for decreasing the other period of each impulse by a corresponding amount, whereby each repeated impulse is divided into two complementary periods having a ratio to each other different than said certain ratio, a second impulse repeater connected to the output of said first repeater for receiving and repeating the impulses repeated by said first repeater, said second repeater including means controlled in accordance with the length of one of the said periods of an impulse received by said

second repeater for making an additional change in the ratio of said periods.

11. In an impulsing system, an incoming circuit and an outgoing circuit, means for impressing spaced apart impulses upon said incoming circuit, a repeater effective responsive to the beginning of each impulse impressed upon said incoming circuit to initiate the transmission of a corresponding impulse over said outgoing circuit and effective responsive to the end of each impulse impressed upon said incoming circuit to terminate the transmission over said outgoing circuit of the corresponding impulse, and adjustable means for varying the speed with which said repeater initiates transmission of an impulse over said outgoing circuit in response to the beginning of the corresponding impulse in said incoming circuit.

12. In an impulsing system, an incoming circuit and an outgoing circuit, means for impressing spaced-apart impulses upon said incoming circuit, a repeater effective responsive to the beginning of each impulse impressed upon said incoming circuit to initiate the transmission of a corresponding impulse over said outgoing circuit and effective responsive to the end of each impulse impressed upon said incoming circuit to terminate the transmission over said outgoing circuit of the corresponding impulse, and adjustable means for varying the speed with which said repeater terminates transmission of an impulse over said outgoing circuit in response to the end of the corresponding impulse in said incoming circuit.

13. In an impulsing system, an incoming circuit and an outgoing circuit, means for impressing spaced apart impulses upon said incoming circuit, a repeater effective responsive to the beginning of each impulse impressed upon said incoming circuit to initiate the transmission of a corresponding impulse over said outgoing circuit and effective responsive to the end of each impulse impressed upon said incoming circuit to terminate the transmission over said outgoing circuit of the corresponding impulse, adjustable means for varying the speed with which said repeater initiates transmission of an impulse over said outgoing circuit in response to the beginning of the corresponding impulse in said incoming circuit and other adjustable means for varying the speed with which said repeater terminates transmission of an impulse over said outgoing circuit in response to the end of the corresponding impulse in said incoming circuit.

14. In an impulsing system, an incoming circuit and an outgoing circuit, means for impressing spaced apart impulses upon said incoming circuit, a repeater effective responsive to the beginning of each impulse impressed upon said incoming circuit to initiate the transmission of a corresponding impulse over said outgoing circuit and effective responsive to the end of each impulse impressed upon said incoming circuit to terminate the transmission over said outgoing circuit of the corresponding impulse, and means effective whenever the time between the end of one impulse impressed upon said incoming circuit and the beginning of the next impulse impressed upon said incoming circuit exceeds a predetermined interval for reducing, in proportion to the excess, the speed with which said repeater initiates transmission of an impulse over said outgoing circuit in response to the beginning of said next impulse.

15. In an impulsing system, an incoming cir-

cuit and an outgoing circuit, means for impressing spaced apart impulses upon said incoming circuit, a repeater effective responsive to the beginning of each impulse impressed upon said incoming circuit to initiate the transmission of a corresponding impulse over said outgoing circuit and effective responsive to the end of each impulse impressed upon said incoming circuit to terminate the transmission over said outgoing circuit of the corresponding impulse, and means effective whenever the time between the end of one impulse impressed upon said incoming circuit and the beginning of the next impulse impressed upon said incoming circuit exceeds a predetermined interval for increasing, in proportion to the excess, the speed with which said repeater initiates transmission of an impulse over said outgoing circuit in response to the beginning of said next impulse.

20. 16. In an impulsing system, an incoming circuit and an outgoing circuit, means for impressing trains of spaced apart impulses upon said incoming circuit, a relay having its winding connected to said incoming circuit to render it responsive to said impulses and having a contact connected to said output circuit to repeat said impulses thereto, and a variable impedance in series with the winding of said relay for adjusting the speed with which said relay operates said contact in response to the beginning of each impulse impressed upon said incoming circuit.

17. An impulsing system as claimed in claim 16, wherein said variable impedance comprises a fixed inductance element in series with said relay winding and a variable non-inductive resistance shunting said element.

18. In an impulsing system, an incoming circuit and an outgoing circuit, means for impressing trains of spaced-apart impulses upon said incoming circuit, a relay having its winding connected to said incoming circuit to render it responsive to said impulses and having a contact connected to said output circuit to repeat said impulses thereto, adjustable means for varying the speed with which said relay operates said contact in response to the beginning of each impulse impressed upon said incoming circuit, and other adjustable means for varying the speed with which said relay operates said contact in response to the end of each impulse impressed upon said incoming circuit.

19. In an impulsing system, an incoming circuit and an outgoing circuit, means for impressing trains of spaced-apart impulses upon said incoming circuit, a relay having its winding connected to said incoming circuit to render it responsive to said impulses and having a contact connected to said output circuit to repeat said impulses thereto, a variable impedance in series with the winding of said relay for adjusting the speed with which said relay operates said contact in response to the beginning of each impulse impressed upon said incoming circuit, and another variable impedance in shunt with the winding of said relay for adjusting the speed with which said relay operates said contact in response to the end of each impulse impressed upon said incoming circuit.

20. In combination, an impedance coil having two windings; a circuit over which one of said windings is energized; contact means operated to interrupt said circuit and, at the same time, to complete another circuit including in series a source of current, a relay and the other winding of said impedance coil; said two windings

being so related to one another that the decay of current in said one winding responsive to the operation of said contact means opposes the increase of current in said other winding and hence delays the operation of said relay.

21. In combination, an impedance coil having two windings; a circuit over which one of said windings is energized; contact means operated to interrupt said circuit and, at the same time, to complete another circuit including in series a source of current, a relay and the other winding of said impedance coil; said two windings being so related to one another that the decay of current in said one winding responsive to the operation of said contact means opposes the increase of current in said other winding and hence delays the operation of said relay; a condenser; a charging circuit for said condenser; a contact controlled by said relay upon operation for interrupting said charging circuit and connecting said condenser in shunt to said relay; means for causing said contact means subsequently to interrupt said series circuit; said condenser thereupon being effective to discharge through said relay to delay the release of said relay.

22. A combination as claimed in claim 21, wherein the shunt circuit across said relay includes, in addition to said condenser, a variable resistor for controlling the discharge of said condenser through said relay.

23. In combination, a relay, an impedance coil, a circuit including said coil and the winding of said relay, a source of current, means for alternately connecting said source to said circuit and disconnecting it therefrom, thereby alternately to operate and release said relay, means for subjecting said impedance coil to a magnetic field immediately prior to each connection of said source to said circuit, and means for varying the strength of said field thereby to control the speed with which said relay operates in response to the connection of said source to said circuit.

24. A combination as claimed in claim 23, wherein said last means causes the strength of said field to vary in proportion to the time in excess of a predetermined interval that said first means causes said source to remain disconnected from said circuit.

25. In combination, an impedance coil having two windings; a relay; means for completing an energizing circuit for one winding of said coil; means operated a variable interval after said circuit is completed for completing another circuit including in series a source of current, the other winding of said coil and the winding of said relay; said relay thereupon effective to operate after a delay whose length depends upon the extent to which said other winding was premagnetized as a result of the prior completion of said first circuit.

26. In combination, two impedance coils each having two windings, a circuit over which one winding of the first impedance coil is energized, means operated to interrupt said circuit and, at the same time, to complete a circuit including in series a source of current, the other winding of

said first coil and one winding of the second impedance coil, means then operated a variable interval of time after said last circuit is completed for completing another circuit including in series a source of current, a relay and the other winding of said second impedance coil, said relay thereupon effective to operate after a delay whose length depends upon the extent to which said other winding of said second impedance coil was premagnetized as a result of said prior operation of said first means.

27. In combination, a relay, impulse operated means for alternately opening and closing an energizing circuit for said relay, an impedance coil having one winding in said circuit to delay the growth of current therein upon each closure of said circuit, a second winding on said impedance coil, and means effective if said energizing circuit remains open for a predetermined interval of time for thereupon completing a circuit for energizing said second winding, whereby upon the subsequent closing of said first circuit the effect of said impedance coil upon the growth of current in said first circuit is modified in accordance with the amount by which said first winding has been premagnetized by said second winding.

28. In combination, a relay having two windings, impulse operated means for alternately opening and closing an energizing circuit for one winding of said relay, a charged condenser, means effective each time said energizing circuit is opened for discharging said condenser an amount proportionate to the time, if any, that said energizing circuit remains open in excess of a predetermined interval, a charging circuit for said condenser completed over the other winding of said relay simultaneously with each closing of said energizing circuit thereby to restore to said condenser any charge removed from it prior to said closing, any charging current flowing through said other winding being effective to oppose the flux generated by said one winding and hence delaying the operation of said relay until the charge is restored to said condenser.

29. In combination, a relay having two windings, impulse operated means for alternately opening and closing an energizing circuit for one winding of said relay, a charged condenser, means effective each time said energizing circuit is opened for discharging said condenser a variable amount, a charging circuit for said condenser completed over the other winding of said relay simultaneously with each closing of said energizing circuit thereby to restore to said condenser the charge removed from it prior to the closing of said energizing circuit, the two windings of said relay being so poled that the energization of said other winding due to the charging current flowing therethrough counteracts the energization of said one winding, thereby to delay the operation of said relay for a period dependent upon the amount by which said condenser was discharged prior to the closing of said energizing circuit.
